ANODE HOUSING FOR A MARINE CATHODIC PROTECTION DEVICE

Edward P. Anderson, Fond du Lac, Wis., assignor to
Brunswick Corporation, Skokie, Ill.

Filed Mar. 29, 1973, Ser. No. 345,892

Term of patent 14 years

Int. Cl. D12—99

U.S. Cl. D12—155

FIG. 1

FIG. 2

FIG. 3

FIG. 4

FIG. 5

FIG. 1 is a perspective view of an anode housing for a marine cathodic protection device of my design;

FIG. 2 is a front view of the anode of FIG. 1;

FIG. 3 is a view of the left side of the anode of FIG. 1;

FIG. 4 is a bottom view of the anode of FIG. 1; and

FIG. 5 is a front view of the anode of FIG. 1.

The appearance of the left and right sides of the anode described above are identical.

I claim:

The ornamental design for an anode housing for a

marine cathodic protection device, substantially as shown and described.
